Attorney.

UNITED STATES PATENT OFFICE

2,076,260

ICE CREEPER

Edward H. Anshelm, New York, N. Y.

Application August 8, 1936, Serial No. 94,947

1 Claim. (Cl. 36—62)

My invention relates to new and useful improvements in ice creepers and has for one of its objects to provide an exceedingly simple and effective device of this character that may be readily and easily applied to and removed from articles of footwear such as shoes, overshoes, rubbers, boots and the like.

Another object of my invention is to produce an ice creeper which is relatively inexpensive in the cost of manufacture although strong and durable and efficient in use.

Another object of my invention is to construct an ice creeper consisting of a strip of metal having its ends turned up to produce flanges which engage the sides of the article of footwear and provided with projections or teeth to engage ice on which the wearer is walking.

A further object of the invention is to form an ice creeper consisting of a narrow flat bar or strip with projections or teeth protruding from opposite faces, one set to engage the sole of the article of footwear and the other set to engage an icy surface.

A still further object of the present invention is to provide an ice creeper consisting of a strip of metal having apertured upturned ends, a set of teeth projecting from the outer face of the strip to engage an ice coated surface, another set of teeth projecting from the inner face of the strip to bite into the sole of an article of footwear and arranged in uniform positions to function as guides, and a strap or equivalent means passing through the apertures in the upturned ends and lying within the space between the second set of teeth, said strap adapted to pass over the toe of the article of footwear and adjustable to various sizes.

With the above and other objects in view this invention consists of the details of construction and combination of elements hereinafter set forth and then designated by the claim.

In order that those skilled in the art to which this invention appertains may understand how to make and use the same I will describe its construction in detail referring by numerals to the accompanying drawing, in which:—

Fig. 1 is a perspective view of an article of footwear with my ice creeper mounted thereon.

Fig. 2 is an enlarged edge view of the ice creeper per se.

Fig. 3 is a bottom or outer face view thereof.

Fig. 4 is a top face or plan view of the same with portions of the securing strap broken away.

Fig. 5 is a sectional view on the line 5—5 of Fig. 3.

Fig. 6 is a sectional view on the line 6—6 of Fig. 3.

In carrying out my invention as herein embodied 10 represents a tread plate consisting of a flat strip or bar of metal having its ends turned up to provide flanges 11 adapted to engage the sides of an article of footwear when the tread plate is placed against the sole of said article of 10 footwear.

The flanges 11 have elongated apertures 12 contiguous the top surface of the tread plate through a strap or equivalent securing means 13 passes so as to lie flat on top of the tread plate. 15 This strap is provided with a buckle 14 whereby it may be adjusted to fit various sized articles of footwear.

A set of teeth 15 project from the top surface of the tread plate and are arranged in two parallel 20 rows adjacent to and parallel with the edges of said tread plate and said rows are spaced a sufficient distance to provide a place for that part of the strap which is superimposed on the tread plate. Said set of teeth 15 are long enough to project above the top surface of the strap material on the upper surface of the tread plate and slightly bite into the sole of the article of footwear on which the creeper is used. Said teeth must only grip the sole because the device is often used 25 on rubbers and if the teeth are very long the rubbers will be damaged.

Another set of teeth 16 project from the bottom surface of the tread plate and can be arranged in any suitable manner of grouping. Said second 30 mentioned set of teeth 16 are designed to grip an ice coated surface to prevent slipping and thus assist a person to travel on foot over icy places.

In producing the teeth 15 and 16, I prefer to 35 partially sever sections from the strip or bar of metal and then turn some up and some down which can be done by the well known process of metal stamping or punching.

To apply an ice creeper of this kind it is only necessary to place the tread plate 10 under the sole of an article of footwear in a location where the flanges 11 will pass over the edges of said article of footwear and then pull the strap 13 taut over the top of the toe of the article of footwear.

With the creeper attached ready for use, as soon as weight is placed thereon, the teeth 15 will grip into the sole of the article of footwear. The creeper is now prevented from moving lengthwise of the article of footwear and the flanges 11 keep it 50 55

from shifting sidewise. Also the teeth 15 hold that portion of the strap which is on top of the tread plate from sliding about.

Of course I do not wish to be limited to the 5 exact details of construction herein shown and described as these may be varied within the scope of the appended claim without departing from the spirit of my invention.

Having thus described my invention, what I 10 claim as new and useful is:—

An ice creeper consisting of a tread plate, upturned flanges at the ends of said plate, said flanges having transversely elongated apertures therethrough contiguous the upper surface of the

plate, downwardly projecting teeth punched from the plate, rows of upwardly projecting teeth also punched from said plate, said rows of upwardly projecting teeth being spaced a distance approximately equal to the length of the apertures in the flanges to form a channel, and an adjustable strap projecting through the apertures in the flanges with a portion thereof imposed on the upper surface of the tread plate and occupying the channel formed between the rows of upwardly projecting teeth to hold the strap against lateral displacement.

EDWARD H. ANSHELM.
